(57) **CLAIM**

The ornamental design for an air conditioning drain line trap, as shown and described.

DESCRIPTION

FIG. 1 is an upper perspective view of an air conditioning drain line trap design;

FIG. 2 is a front view of the design of FIG. 1;

FIG. 3 is a first side view of the design of FIG. 1;

FIG. 4 is a second side view of the design of FIG. 1;

FIG. 5 is a rear view of the design of FIG. 1;

FIG. 6 is a top view of the design of FIG. 1; and,

FIG. 7 is a bottom view of the design of FIG. 1.

The broken line disclosure represents unclaimed portions of the air conditioning drain line trap in which the design is embodied.
